DEVICE FOR FEATHERING ARROWS

Charles F. Birchall, Lancaster, Pa.

Application June 21, 1933. Serial No. 676,970

6 Claims. (Cl. 273—106.5)

This invention relates to a device for feathering arrows and has for its object to provide, in a manner as hereinafter set forth, a device of the class referred to constructed and arranged to enable for expeditiously and conveniently attaching feathers in suitable spaced relation to the shaft of an arrow.

The standard method of attaching feathers to arrows is to provide for securing them at 120° apart to the arrow shaft and with the cock feather disposed at right angles to the shaft. It is the aim of this invention to provide, in a manner as hereinafter set forth, a device which will enable for easily and accurately attaching feathers with respect to the arrow shaft in the position as referred to.

Further objects of the invention are to provide, in a manner as hereinafter set forth, a device for the purpose referred to which is comparatively simple in its construction and arrangement, strong, durable, thoroughly efficient in its use, conveniently operated and comparatively inexpensive to manufacture.

To the above ends essentially, and to others which may hereinafter appear, the invention consists of such parts and such combination of parts which fall within the scope of the invention as claimed.

In the drawing:

30 Figure 1 is a longitudinal sectional view of the device as applied to the shaft of an arrow for attaching feathers thereto in the desired spaced relation.

Figure 2 is an end elevation of the device.

35 Figure 3 is a section on line 3—3 Figure 1.

Figure 4 is an elevation looking toward the outer face of one of the arrow shaft supports.

The device includes a pair of oppositely disposed arrow shaft supports 1, 2 and each of which 40 includes a circular member 3 formed of a body part 4 of cup-shaped cross section and an annular rim 5 at the open end of body part 4. The latter when member 3 is in position relative to the nock of the arrow shaft 6 opens outwardly. The member 3 axially thereof is formed with an opening 7 for the shaft. Formed integral with the outer face of the bottom or base of body part 4 and registering with the wall of opening 7 is an outwardly directed resilient sleeve. The sleeve 45 of support 1 is designated 8 and that of support 50 of support 2 is designated 9. Each sleeve is split from end to end, as at 10. Anchored to the inner face of the bottom or base of body part 4 is a set of channel-shaped feather holder positioners 11 which extend from the wall of opening 7 to the outer face of the

side of body part 4. The positioners 11 are radially disposed with respect to the axes of the supports. Each set consists of three positioners and which are spaced 120° apart. The positioners 11 of one support align with the positioners 11 of the other support. The positioners 11 are arranged in pairs and each pair is adapted to removably receive a feather holder to be referred to. The positioners 11 provide guide grooves 12 which are open at the inner and outer ends 65 thereof. The sleeve 8 of support 1 is provided in proximity to its outer end with a diametrically extending pin 13 which is fixedly secured to the sleeve and provides an abutment for the nock end of shaft 6. The rim 5 is formed with a set 70 of three bayonet-shaped slots 14 opening at the edge thereof and with the inner ends of said slots arranged 120° apart. The purpose of the slots will be referred to.

The nock end of the arrow shaft 6 is bifurcated 75 at its rear terminal portion to provide a nock 15. The nock end of shaft 6 is adapted to have mounted thereon the supports 1, 2 and with the latter arranged in spaced relation. The arrow shaft 6 extends through sleeve 9, bridges the space 80 between the supports 1, 2, extends into sleeve 8 and abuts pin 13. The bifurcated rear terminal portion 15 of the shaft 6 provides for the latter being mounted on pin 13. The latter prevents the end of shaft 6 from extending from the outer 85 end of sleeve 8 and brings one of the positioners 11 at right angles to arrow nock 15.

When the supports 1, 2 are mounted on the arrow shaft 6, they are detachably clamped to the latter, and for such purpose a pair of split resilient clamps 16, 17 are mounted on the sleeves 8, 9 respectively. The clamps function to frictionally bind the sleeves and arrow shaft 6 together.

The device includes a set of spring controlled 95 feather holders 18 of a number corresponding to that of the pairs of positioners 11. Each holder is of like construction and the description of one will apply to the other. Each holder includes a clamp 19 for the feather 20 and a combined pivot 100 and retainer 21 for clamp 19. The latter includes a pair of inverted T-shaped clamping plates of like form and each of which consists of a head 22 and an outwardly directed stem 23 which at its inner end merges into and centrally with respect 105 to the outer side of the head 22. The stem 23 of each plate is provided with a pair of inwardly extending parallel spaced apertured ears 24. The ears 24 of one clamping plate are arranged between the ears 24 of the other plate. Positioned 110

- between the stems 23 of the clamping plates is a controlling spring 25 functioning normally to maintain the stems extended relatively to each other and the heads in clamping position. The 5 spring 25 is set up with a loop 26 and a pair of oppositely extending end terminal portions 27, one permanently bearing against the inner face of one and the other against the inner face of the other stem.
- 10 The combined pivot and retainer 21 is in the form of an elongated resilient bar 28 provided at each end with a loop or eye 29. The bar 28 extends through the apertured ears 24 and the loop 26 of spring 25 and constitutes a pressure applying means for the holder and acts in a manner to give a direct pressure against the stem of the arrow feather to cause a thoroughly efficient gluing. Very few feathers are the same thickness at both ends and retainer 21 allows holder 18 to 15 take care of this unequal thickness.
- 15 The slots 14 in one rim, when the supports 1, 2 are mounted on the arrow shaft 6 align with the slots 14 in the other rim, and by this arrangement the slots 14 of the supports are disposed in 20 pairs. Each pair is for the reception of a bar 28 for detachably locking it in position for the purpose of maintaining a holder in a manner to retain the feather against the arrow shaft 6.
- 20 When using the device, support 2 is positioned 25 on shaft 6 of the arrow for about four inches with the positioners 11 thereon extended towards the nock 15. Support 1 is then slid upon arrow shaft 6 until pin 13 abuts the base of nock 15 and with the positioners 11 thereof extended 30 away from the nock. The clamp 16 is then mounted in position binding arrow to support 1. One end of a holder 18 is then slipped into one of the positioners 11 on support 1, support 2 is shifted towards support 1 so that one of the 35 positioners 11 on support 2 will receive the other end of the holder whereby proper spacing will be had between the supports. The clamp 17 is then mounted in position binding arrow to support 2. The holder 18 is then removed and a feather is positioned between and clamped to the 40 heads 22 of the holder. Glue is then applied to the feather. The heads 22 of holder 18 with the feather are extended through a pair of aligned positioners 11 and that part of the feather provided with the glue is mounted against the periphery of the shaft of the arrow. The 45 retainer 21 forming part of the holder is positioned in a pair of aligning slots 14 latched in the latter and acting on a clamp 19 will hold the feather against the arrow shaft until the glue has hardened sufficiently to secure the feather in position.
- 50 The device may be made of copper, brass, sheet iron, zinc or tin and the parts of the supports may be assembled by soldering, welding or riveting.
- 55 Owing to the structural arrangement of the device, it does not require experience to attach feathers to arrows, and the work accomplished by the device will be on a par with a factory made arrow.
- 60 The device, during the gluing operation will permit of viewing the feather to an extent to permit of checking any mistake before the glue hardens.
- 65 What I claim is:—
- 70 1. A device for feathering arrows including a pair of oppositely disposed removable supports having aligning feather positioners on the opposed faces thereof and means for mounting said supports on the arrow, resilient elements mounted
- 75 on said means for detachably clamping the supports to the arrow, and a releasable spring controlled feather holder extending between the supports and removably and slidably mounted in said aligned positioners for placing the glue carrying part of a feather lengthwise of the arrow and including means connected with said holder and detachably engaging in said supports for maintaining said part against the arrow until the glue sets. 80
- 85 2. A device for feathering arrows including a pair of oppositely disposed removable supports having aligning feather positioners on the opposed faces thereof and means for mounting said supports on the arrow, resilient elements mounted on said means for detachably clamping the supports to the arrow, a releasable spring controlled feather holder extending between the supports and removably and slidably mounted in said aligned positioners for placing the glue carrying part of a feather lengthwise of the arrow and including means connected with said holder and detachably engaging in said supports for maintaining said part against the arrow until the glue sets, the said supports being formed with bayonet-shaped slots opening at the outer edges thereof, and the said means of the holder being in the form of a resilient bar engaging said slots. 90
- 95 3. A device for feathering arrows including a pair of oppositely disposed removable supports having aligning feather positioners on the opposed faces thereof and means for mounting said supports on the arrow, resilient elements mounted on said means for detachably clamping the supports to the arrow, a releasable spring controlled feather holder extending between the supports and removably and slidably mounted in said aligned positioners for placing the glue carrying part of a feather lengthwise of the arrow and including means connected with said holder and detachably engaging in said supports for maintaining said part against the arrow until the glue sets, the said supports being formed with bayonet-shaped slots opening at the outer edges thereof, and the said means of the holder being in the form of a resilient bar engaging said slots. 100
- 105 4. A device for feathering arrows including a pair of oppositely disposed removable supports having aligning feather positioners on the opposed faces thereof and means for mounting said supports on the arrow, resilient elements mounted on said means for detachably clamping the supports to the arrow, a releasable spring controlled feather holder extending between the supports and removably and slidably mounted in said aligned positioners for placing the glue carrying part of a feather lengthwise of the arrow and including means connected with said holder and detachably engaging in said supports for maintaining said part against the arrow until the glue sets, the said supports being axially apertured and the said means of said supports being in the form of split sleeves registering with the apertures of the supports. 110
- 115 5. A device for feathering arrows including a pair of oppositely disposed removable supports having aligning feather positioners on the opposed faces thereof and means for mounting said supports on the arrow, resilient elements mounted on said means for detachably clamping the supports to the arrow, a releasable spring controlled feather holder extending between the supports and removably and slidably mounted in said aligned positioners for placing the glue carrying part of a feather lengthwise of the arrow and including means connected with said holder and detachably engaging in said supports for maintaining said part against the arrow until the glue sets, the said supports being axially apertured and the said means of said supports being in the form of split sleeves registering with the apertures of the supports. 120
- 125 6. A device for feathering arrows including a pair of oppositely disposed removable supports having aligning feather positioners on the opposed faces thereof and means for mounting said supports on the arrow, resilient elements mounted on said means for detachably clamping the supports to the arrow, a releasable spring controlled feather holder extending between the supports and removably and slidably mounted in said aligned positioners for placing the glue carrying part of a feather lengthwise of the arrow and including means connected with said holder and detachably engaging in said supports for maintaining said part against the arrow until the glue sets, the said supports being axially apertured and the said means of said supports being in the form of split sleeves registering with the apertures of the supports, the said supports being formed with bayonet-shaped slots opening at the outer edges thereof, and the said means of the holder being in the form of a resilient bar engaging said slots. 130
- 135 7. A device for feathering arrows including a pair of oppositely disposed removable supports having aligning feather positioners on the opposed faces thereof and means for mounting said supports on the arrow, resilient elements mounted on said means for detachably clamping the supports to the arrow, and a releasable spring controlled feather holder extending between the supports and removably and slidably mounted in said aligned positioners for placing the glue carrying part of a feather lengthwise of the arrow and including means connected with said holder and detachably engaging in said supports for maintaining said part against the arrow until the glue sets, the said supports being axially apertured and the said means of said supports being in the form of split sleeves registering with the apertures of the supports, the said supports being formed with bayonet-shaped slots opening at the outer edges thereof, and the said means of the holder being in the form of a resilient bar engaging said slots. 140
- 145 8. A device for feathering arrows including a pair of oppositely disposed removable supports having aligning feather positioners on the opposed faces thereof and means for mounting said supports on the arrow, resilient elements mounted on said means for detachably clamping the supports to the arrow, and a releasable spring controlled feather holder extending between the supports and removably and slidably mounted in said aligned positioners for placing the glue carrying part of a feather lengthwise of the arrow and including means connected with said holder and detachably engaging in said supports for maintaining said part against the arrow until the glue sets, the said supports being axially apertured and the said means of said supports being in the form of split sleeves registering with the apertures of the supports, the said supports being formed with bayonet-shaped slots opening at the outer edges thereof, and the said means of the holder being in the form of a resilient bar engaging said slots. 150

trolled feather holder extending between the supports and removably and slidably mounted in said aligned positioners for placing the glue carrying part of a feather lengthwise of the arrow and including means connected with said holder and detachably engaging in said supports for maintaining said part against the arrow until the glue sets, said holder including clamping plates pivotally connected together by the said means thereof. 5

6. A device for feathering arrows including a pair of oppositely disposed removable supports having aligning feather positioners on the opposed faces thereof and means for mounting said supports on the arrow, resilient elements mounted on said means for detachably clamping the supports to the arrow, a releasable spring controlled feather holder extending between the supports and removably and slidably mounted in said aligned positioners for placing the glue carrying part of a feather lengthwise of the arrow and including means connected with said holder and detachably engaging in said supports for maintaining said part against the arrow until the glue sets, said holder including clamping plates pivotally connected together by the said means thereof, the said supports being formed with bayonet-shaped slots opening at the outer edges thereof, and the said means of the holder being in the form of a resilient bar engaging said slots. 10 15 80 85 90
